(57) CLAIM

The ornamental design for a tablet holder, as shown and described.

DESCRIPTION

FIG. 1 is a front perspective view of a tablet holder;

FIG. 2 is a front view thereof;

FIG. 3 is a rear view thereof;

FIG. 4 is a top view thereof;

FIG. 5 is a bottom view thereof;

FIG. 6 is a left side view thereof; and,

FIG. 7 is a right side view.

The hatched lines represent surface shading.

The broken lines shown in FIGS. 1-2 and 4-7 represent unclaimed subject matter and form no part of the claim design.

1 Claim, 6 Drawing Sheets
